United States Patent Office

Des. 215,313
Patented Sept. 23, 1969

215,313

AMUSEMENT RIDE AUTO

Robert H. Gurr, Los Angeles, Calif., assignor to Wed Enterprises, Inc., Glendale, Calif., a corporation of California

Filed Nov. 14, 1968, Ser. No. 14,446

Term of patent 14 years

Int. Cl. D21—04

U.S. Cl. D34—5

FIG.1

FIG.2

FIG.3

FIG.4

FIG.5

FIG.6

FIG. 1 is a perspective view of an amusement ride auto showing my new design;

FIG. 2 is a side elevational view thereof;

FIG. 3 is a front elevational view thereof;

FIG. 4 is a top plan view thereof;

FIG. 5 is a side elevational view thereof showing the side opposite that shown in FIG. 2; and

FIG. 6 is a rear elevational view thereof.

I claim:

The ornamental design for an amusement ride auto, substantially as shown and described.
